CUTTING APPARATUS

Bollie M. Jansen and Fred L. Kitley,
Caldwell, Ohio

Application January 13, 1944, Serial No. 518,142

2 Claims. (Cl. 164—73)

Our invention relates to improvements in cutting apparatus, the principal object in view being to provide simply constructed, inexpensive, portable apparatus for quickly and easily cutting sheet material such as commercially designated "Transite," which is of a texture such that sawing of the same is impracticable and frequently results in irreparable injury to saws.

Other and subordinate objects are also comprehended by our invention, all of which, together with the precise nature of our improvements, will be readily understood when the succeeding description and claims are read with reference to the drawings accompanying and forming part of this specification.

In said drawings:

Figure 1 is a view in perspective illustrating our improved cutting apparatus in its preferred embodiment.

Figure 2 is a fragmentary view in longitudinal section, drawn to an enlarged scale.

Figure 3 is a view in transverse section taken on the line 3—3 of Figure 2.

Figure 4 is a similar view in transverse section taken on the line 4—4 of Figure 1, and

Figure 5 is another similar view taken on the line 5—5 of Figure 2.

Referring to the drawings by numerals, in the preferred embodiment thereof, our improved cutting apparatus comprises an elongated, rectangular platform 1, of any suitable size, embodying longitudinally extending, tongue and groove planks 2 suitably secured to and adapted to be supported by end and intermediate cross cleats 3, 4, a pair of contiguous planks 2 being spaced apart in the longitudinal center of the platform 1 to provide a central, longitudinal slot 5, and said cleats being notched, as at 6, below said slot. A pair of angle iron bars 7 are mortised into the before mentioned contiguous planks 2, respectively, to extend down through the slot 5 and provide metal sides for the same. Screws 8 secure the bars 7 in place. The corner edges of the bars 7 form ribs 9 at the top of the slot 5 for a purpose presently seen. A pair of spacing collars, one of which is shown at 10, are provided in the slot 5 between the bars 7 adjacent each end of the slot 5, with bolts extended through the same and said bars, as at 11, and equipped with nuts 12. As will be understood, the bars 7 depend below the planks at opposite sides of the slot 5 to provide clear, lower edges 13 on said bars. The slot 5 serves as a guide for a rocking cutter tool now to be described.

The tool 14 comprises a flat, metal head 15,

substantially oval shape, and extending lengthwise downwardly through the slot 5, and which is provided at its upper end with a flat shank 16 extending obliquely from the head. A bifurcated handle bar 17 straddles the free end of the shank 16 and is bolted thereto, as at 18, to extend therefrom. Above and below the slot 5, which is to say the bars 7, the head 15 is provided with upper and lower pairs of aligned, lateral studs 19, 20 extending from opposite sides of said head. Intermediate the pairs of studs 19, 20 said head is provided with side bosses 21 fitting loosely between the bars 7. The shank 16, intermediate the head 15 and the handle bar 17, is provided with a toothed lower edge, the teeth 22 of which are pitched forwardly and are flat faced, as best shown in Figure 5.

In using the described apparatus, the sheet 23 is placed on the platform 1, as shown in dotted lines in Figure 1. The described tool 14 is pulled along the slot 5 until the teeth 22 overlie the near edge of said sheet. The tool 14 is then rocked downwardly to force the teeth 22 through the sheet with the lower pair of studs 20 fulcruming against the lower edges 13 of the bars 7. Said tool is then rocked upwardly with the upper pair of studs 19 fulcruming on top of the bars 7 to withdraw the lower edge or teeth 22 out of the cut, then pulled along the slot 5 to position the teeth 22 for another cutting operation and then again rocked downwardly, as previously described, to effect another cut in said sheet. The operations described are repeated until the sheet is completely, or partially, severed, as desired. The bosses 21 and the ribs 9 prevent the tool from wobbling sideways during operation thereof, the advantage of which will be clear.

The foregoing will, it is believed, suffice to impart a clear understanding of our invention without further explanation.

Manifestly, the invention, as described, is susceptible of modification without departing from the inventive concept, and right is herein reserved to such modifications as fall within the scope of the appended claims.

What we claim is:

1. In apparatus of the class described, a platform structure comprising supporting cleats, said structure having a central slot therein extending from side to side thereof, metal bars lining the sides of the slot, and a cutter tool including a handle, and a head slidable in said slot and adapted to be rocked vertically by said handle, and upper and lower pairs of studs on said head overlying and underlying said bars, respectively.

for engagement with the bars to form fulcrum members during rocking of the head, said pairs of studs being spaced apart a distance greater than the width of said bars to prevent binding of the studs against the upper and lower edges of the bars and thereby provide for free rocking movement of said head.

2. In apparatus of the class described, a platform structure comprising supporting cleats, said structure having a central slot therein extending from side to side thereof, metal bars lining the sides of the slot, and a cutter tool including a

handle, and a head slideable in said slot and adapted to be rocked vertically by said handle, and upper and lower pairs of studs on said head overlying and underlying said bars, respectively, for engagement with the bars to form fulcrum members during rocking of the head, said tool including a shank extending from the head and provided with a toothed cutting edge overlying said slot, said teeth being flat faced and pitched toward the head.
